INVENTOR.

Anthony E. Carlson,
BY

Robt. W. Pearson
ATTORNEY.

UNITED STATES PATENT OFFICE.

ANTHONY E. CARLSON, OF LOS ANGELES, CALIFORNIA.

APPARATUS FOR ELEVATING AND LOWERING OIL-WELL TUBING.

Application filed February 6, 1926. Serial No. 86,627.

This invention relates to apparatus for elevating and lowering oil well tubing, and the general object of the invention is to provide a simple, quick-acting, and efficient apparatus for raising and lowering oil well tubing, which may be easily and readily applied to the tubing for raising or lowering the same, or be removed from the tubing as desired.

10 Other objects and advantages will appear hereinafter.

The invention is illustrated in the annexed drawing which forms a part of this specification and in which:

15 Fig. 1 is a view partly in vertical longitudinal section and partly in elevation of my invention shown mounted in an oil well derrick and applied to the well tubing for raising or lowering the same.

20 Fig. 2 is a horizontal section of Fig. 1 taken on line 2—2.

Corresponding reference characters designate the same parts in all the views.

The spider 1 is formed with a square base 3 provided with a central opening 4, which base rests upon the derrick foundation timbers 5, said base being formed with a depending flange 6 a short distance inwardly from the edges thereof, which flange 25 engages the inner side of said timbers and centers the base and its opening 4 over the well. A pair of upstanding members 7 are formed on the base 3 at opposite sides of the opening 4. A pair of jaws 8 are each formed with a pair of spaced outwardly depending ears 9, each of which pairs of ears straddles the member 7 and is fulcrumed thereto by a fulcrum pin 10. A pair of levers 11 are formed with forks 12 respectively, each of which forks straddles the pair of ears 9 and is secured thereto by a pin 13 extending through the side members 14 of the fork and through the ears, the lower inner ends of the side members of one fork being pivotally connected to the lower inner ends of the side members of the other fork by pivot pins 15.

The jaws 8 are of semi-circular formation so that when brought together by the levers 20 11 they will fit entirely around the well tubing T when elevated from the well through the opening 4 in the base 3. The jaws 8 are formed with recesses 16 in their gripping faces extending downwardly from the upper side of the jaws in which recesses are fitted slips 17, there being grooves 18 in the

bottom of said recesses in which fit securing tongues 19 on the bottom of said slips, whereby the slips are prevented from falling inwardly from the recesses when the jaws 25 are removed from the tubing. The slips are formed with gripping edges 20 on their gripping faces, which edges extend horizontally of the slips. The meeting edges of the jaws 8 are formed with outstanding flanges 21 formed with grooves 22 in their outer sides to receive rings 23 for holding the jaws 20 loosely together, permitting a slight relative opening and closing movement of the jaws so that the jaws may fit the tubing of 70 slightly varying diameters. Set screws 24 are provided in the flanges 21 of one of the jaws for engaging the flange of the other jaw for adjustably limiting the closing movement of the jaws. A split collar 25 rests on top of the jaws 8 with one section 26 of the collar resting upon one jaw and the other section resting on the other jaw, there being securing tongues 27 on the under side of the collar sections fitting in 80 grooves 27' in the top of the jaws, whereby the collar sections are prevented from being displaced from the jaws. The tubing couplings C are adapted to rest upon the collar 25 to support the tubing at different elevations, the weight of the tubing being placed by said collars C upon the collar 25 and jaws 8, whereby the jaws are swung inwardly on their fulcrums 10 and the edges 20 of the slips 17 caused to be pressed into 90 the tubing to grip the same firmly, the engagement of the set screws 24 with the flanges 21 of the opposite jaws limiting the inward movement of the jaws and the gripping depth to which the edges 20 are pressed into the tubing. The collar 25 engages the upper edges of the slips 17 and hold them in the recesses 16 so that they cannot be lifted out. To a side member 14 of the fork 12 of one of the levers 11 is connected a hook 100 28 for engaging an opening 29 in one of the base members 7 for holding the jaws 8 open so that the tubing T may be freely raised and lowered through the spider 1.

In operation the spider 1 holds the tubing 105 against falling. The jaws 8 swing open freely when the tubing is lifted and the weight thereof taken off the jaws, but said jaws swing together and grip the tubing when the tubing is lowered and the weight thereof is applied to the jaws by the engagement 110 of a tubing collar C with the jaw collar 25.

Having thus described my invention what I claim is:

1. An apparatus as disclosed including a spider, said spider comprising a base constructed and arranged to rest upon the derrick foundation, a pair of jaws pivotally mounted on said base for engaging the well tubing under a coupling thereof, a pair of levers pivotally connected together and to said jaws respectively.
2. An apparatus as disclosed including a spider, said spider comprising a base, a pair of jaws pivotally mounted on said base for engaging the well tubing under a coupling thereof, a pair of levers pivotally connected together and to said jaws respectively, and slips fitted in said jaws for gripping the tubing.
3. An apparatus as disclosed including a spider, said spider comprising a base, a pair of jaws pivotally mounted on said base for engaging the well tubing under a coupling thereof, a pair of levers pivotally connected together and to said jaws respectively, and a split collar mounted on top of the jaws with one section of the collar on one jaw and the other section of the collar on the other jaw, on which collar is adapted to rest the tubing coupling.
4. An apparatus as disclosed including a spider, said spider comprising a base, a pair of jaws pivotally mounted on said base for engaging the well tubing under a coupling thereof, a pair of levers pivotally connected together and to said jaws respectively, slips fitted in said jaws for gripping the tubing, and a split collar mounted on top of the jaws over said slips with one section of the collar on one jaw and the other section of the collar on the other jaw, on which collar is adapted to rest the tubing coupling.
5. An apparatus as disclosed including a spider, said spider comprising a base, a pair of jaws pivotally mounted on said base for engaging the well tubing under a coupling thereof, a pair of levers pivotally connected

together and to said jaws respectively, slips secured in said jaws for gripping the tubing, and a split collar secured on top of the jaws over said slips adapted to hold said slips in locked position between said jaws and collars, with one section of the collar on one jaw and the other section of the collar on the other jaw, on which collars is adapted to rest the tubing coupling.

6. An apparatus as disclosed including a spider, said spider comprising a base constructed and arranged to rest upon the derrick foundation, a pair of jaws pivotally mounted on said base for engaging the well tubing under a coupling thereof, a pair of levers pivotally connected together and to said jaws respectively, and means for adjustably limiting the closing of the jaws.

7. An apparatus as disclosed including a spider, said spider comprising a base, constructed and arranged to rest upon the derrick foundation, a pair of jaws pivotally mounted on said base for engaging the well tubing under a coupling thereof, a pair of levers pivotally connected together and to said jaws respectively, and means for holding the jaws closed.

8. An apparatus as disclosed including a spider, said spider comprising a base constructed and arranged to rest upon the derrick foundation, a pair of jaws pivotally mounted on said base for engaging the well tubing under a coupling thereof, a pair of levers pivotally connected together and to said jaws respectively, and means for holding said jaws open.

9. An apparatus as disclosed including a spider, said spider comprising a base, a pair of jaws pivotally mounted on said base for engaging the well tubing under a coupling thereof, and a pair of levers pivotally connected together and to said jaws respectively.

In testimony whereof I hereunto affix my signature.

ANTHONY E. CARLSON.
